UNITED STATES PATENT OFFICE

EARL W. LITTLE, OF INDIANAPOLIS, INDIANA

METHOD OF ASSEMBLING CAGE TOPS

Application filed December 7, 1928. Serial No. 412,302.

This invention relates to method of assembling the top of bird cages, particularly of the Japanese type and one feature of the invention is the means of assembling the top forming wires together in the form of a substantially cone shaped roof and rigidly anchoring the top ends thereof to a supporting plate.

A further feature of the invention is in so constructing the top portion of the cage that it may be welded or otherwise secured to the body of the cage structure with a minimum of welding operations and at the same time constitute a very rigid connection between these parts.

A further feature of the invention is in so anchoring the upper ends of the top forming wires that when suspended from a support, a more or less direct longitudinal pull will be directed against said wires.

A further feature of the invention is the provision of an endless, substantially channel shaped band for concealing the extreme lower ends of the top forming wires from view and at the same time give an ornamental effect to the completed cage.

A further feature of the invention is in constructing the top forming wires that they will snap into position within the channel of the band fitting over the ends thereof, when the assembled top forming wires are drawn bodily through the band.

A further feature of the invention is the provision of means for reinforcing the lower end portions of the top forming wires and rendering them sufficiently rigid that the ends thereof will remain normally seated within the channel of the band after being snapped thereinto.

Other objects and advantages will be hereinafter more fully set forth and pointed out in the accompanying specification.

In the accompanying drawings which are made a part of this application,

Figure 1 is a top plan view of a bird cage top partially assembled.

Figure 2 is a sectional view of the top in assembled relation with the body of the cage as seen along line 2-2, Fig. 1.

Figure 3 is a transverse sectional view

through the top portion showing the position of the wires with the band before being drawn through the band, and,

Figure 4 is a similar view showing the position of the top forming wires just prior to snapping into the band.

Referring to the drawings, in which similar reference numerals designate corresponding parts throughout the several views, the numeral 1 designates the body forming wires of the cage, which are vertically arranged, with the upper end portions thereof connected with encircling wire bands 2 and 3, preferably by spot welding, the band 3 being preferably at the extreme top ends of the wires 1.

Extending over the upper ends of the body forming wires 1, are the top forming wires 4, which are preferably arcuately arranged to form a substantially cone shaped top, said wires 4, adjacent their lower ends, resting upon the band 3, to which certain of them are secured, preferably by spot welding, as shown at 5, in Fig. 2.

In order to conceal the extreme lower ends of the wires 4 from view, a metal band 8, substantially channel shaped in cross section, is placed over said ends and secured thereto, preferably by spot welds 9, which are placed at suitable intervals around the band, the band 8 being of considerable width and provided at its edges with beads 10 for rendering the same more or less ornamental. The band 8 is preferably constructed in a single length and then bent into circular formation and the ends thereof secured together, preferably by spot welding, so that when the welded portion is properly treated, the band will have the appearance of a continuous surface.

Substantially mid-way between the point of connection of the wires 4 with the band 3 and the band 8, a band 6 is introduced below the wires 4 and secured thereto, preferably by spot welds, as indicated at 7, Fig. 2, each wire 4 being welded to the ring or band 6, thereby making said wires 4 extremely rigid at this point and preventing undue bending of the projecting portions of the wires.

The top ends of the wires 4 are provided

with hook terminals 11, which fit over and interlock with a vertically extending flange 12 of an anchoring and supporting plate 13, the hook terminals 11 being so arranged that 5 a pull will be directed lengthwise of the wires 4, when the cage is suspended by the plate 13. The plate 13 is so constructed that a valley 14 is formed adjacent the flange 12 and by introducing solder or the like into 10 this valley and over and between the terminals 11, said terminals will be securely anchored to the plate 13.

In assembling the top portion, the wires 4 are positioned to engage the terminals 11 15 with the flange 12 and are then soldered thereto. The lower ends of the wires 4 are then entered in the channel of the band 8, by drawing the assembled wires upwardly through the band 8, or forcing the band over 20 the ends of the wires, after which the band 6 is positioned below the wires 4 and welded thereto as described. The top so formed is then placed over the upper end of the body of the cage and certain of the wires 4 welded 25 to the band 3, but owing to the rigidity of the top and body portions, the number of welds required to properly anchor the top to the body are limited, thus making a great saving in time of manufacture. 30 By assembling the parts of the cage structure in the manner described, a very strong and durable structure is provided, while the cost of production is reduced to a minimum, without weakening any parts of the cage 35 structure.

What I claim is:

1. A method of assembling the top portion of a cage structure consisting in anchoring the upper ends of a plurality of top forming wires, entering the lower ends of said wires in a substantially channel shaped band, and welding an additional band to said wires at 40 a point above said first band.
2. A method of assembling the top of a cage consisting in anchoring the upper ends of a plurality of radiating top forming wires, forcing the free lower ends thereof to snap into the groove of an endless band, and securing a reinforcing and retaining band 45 to one face of said top forming wires adjacent their point of entrance into the grooved band.
3. A method of assembling the top of a cage consisting in anchoring the upper ends of a plurality of top forming wires and imparting spring action to the lower free ends thereof, contracting the free ends of said wires and entering them into the channel of a channel shaped band, and welding a re- 50 forcing and retaining band to one face of each of said top forming wires.
4. A method of assembling the top of a cage consisting in anchoring the upper ends of a plurality of top forming wires, drawing or forcing the free ends of said wires into 55

the groove of a channel shaped band and welding a reinforcing and retaining band to said top forming wires in juxtaposition to said channel shaped band to prevent bending of the wires adjacent the lower ends 70 thereof.

In testimony whereof, I have hereunto set my hand on this the 26 day of November, 1929, A. D.

EARL W. LITTLE. 75
